SACHET

Ellie Marie Fetterer, Sheboygan, Wis.

Application January 24, 1949, Serial No. 431

Term of patent 3½ years

(Cl. D86—10)

To all whom it may concern:

Be it known that I, Ellie Marie Fetterer, a citizen of the United States of America, and residing at Sheboygan, in the County of Sheboygan and State of Wisconsin, have invented a new, original, and ornamental Design for a Sachet, of which the following is a specification, reference being had to the accompanying drawing, forming a part thereof.

In the drawing:

Fig. 1 is a three quarter front perspective view of a sachet, showing my new design.

Fig. 2 is a rear elevational view of my new design.

Fig. 3 is a top plan view of my new design.

I claim:

The ornamental design for a sachet, as shown.
ELLIE MARIE FETTERER.
